ARTICLE WRAPPING APPARATUS

Constantine S. Stephano, Meadowbrook, Pa., assignor to Stephano Brothers, Philadelphia, Pa., a corporation of Pennsylvania

Application September 12, 1949, Serial No. 115,151

9 Claims. (Cl. 53—149)

1

This invention relates to article handling machinery, more particularly to an improved conveyor system for cigarette packaging machines.

A disadvantage of previous construction in cigarette packaging machinery resided in the difficulty of transferring the cigarettes from one station in the wrapping machine to a subsequent station. The improvements in the present machine relate to the proper timing, spacing and feeding of individual cigarettes, which have previously been partially wrapped in individual wrappers, to the station on the wrapping machine where the ends of the wrappers are folded and sealed.

A primary object of the invention, therefore, is to provide in article-handling machinery a pair of feed screws onto which the articles to be wrapped are deposited and from thence carried to a station where further steps in the wrapping procedure are performed.

A still further object of the invention is to provide an improved feed screw construction for use in individual cigarette wrapping machines.

A still further object of the invention is to provide an improved means for end-wrapping individual cigarettes.

A still further object of the invention is to provide an improved end-sealer for cigarette wrapping machines.

Further objects will be apparent from the specification and drawings in which:

Fig. 1 is a perspective, partly broken away, showing a cigarette wrapping machine incorporating features of the present invention;

Fig. 2 is a fragmentary elevation showing one of the feed screws of the apparatus of Fig. 1;

Fig. 3 is an enlarged transverse sectional detail as seen at 3—3 of Fig. 1;

Fig. 4 is an enlarged longitudinal sectional detail as seen at 4—4 of Fig. 1;

Fig. 5 is a transverse sectional detail as seen at 5—5 of Fig. 4; and

Fig. 6 is an enlarged transverse sectional detail as seen at 6—6 of Fig. 1.

A machine for individually wrapping articles such as cigarettes comprises a conical separator assembly 10 having individual compartments 11, 11 adapted to receive partially wrapped cigarettes 12, 12. The rotating member 10a of separator 10 is mounted on a shaft 13 which is driven from shaft 14 by means of a pair of bevel gears 15 and 16. The cigarettes, after the initial wrapping operation, are fed into member 10a by means of endless belts 17 and 18. The construction and operation of the feed to separator 10 as well as the separator itself form no part of the present

2

invention and are well known in the cigarette wrapping art.

The member 10a rotates within a guard 10b which terminates at a point near the bottom of the separator as shown in Fig. 2. When the cigarettes reach the terminus of the guard 10b, they are deposited one by one onto a pair of feed screws 25 and 26, which are journaled at one end in plate 27 and at the opposite end in bracket 28. Feed screws 25 and 26 are counter-rotating and are interconnectingly driven by means of spur gears 29 and 30. The shaft of screw 25 extends through plate 27 and is provided with a sprocket 31 which is in turn driven by a chain 32 connected to suitable driving means (not shown).

The pitch of threads 33 and 34 on screws 25 and 26 is the same for each screw and constant throughout the length of the screws. The gaps or spaces between adjacent threads on each screw 20 are so timed that there is a gap at the top of each screw which is transversely in registry with a corresponding gap on the adjacent screw so that cigarettes which are individually deposited from separator 10 fall between adjacent threads on each screw and thence are carried axially on the screws away from the loading station. The thickness of threads 33 and 34 is not uniform throughout the length of the screws as will be explained more fully hereinafter.

Referring now particularly to Fig. 1, it will be seen that as the cigarettes are deposited onto screws 25 and 26, they are carried by the threads 33 and 34 of the screws to an aligning station which comprises a pair of brackets 35 and 36 mounted on platform 37 and having flared openings 38 and 39 into which the cigarettes are fed. Brackets 35 and 36 have horizontal flanges 35a and 36a which slightly overlap the tops of the cigarettes. As the cigarettes emerge from contact from brackets 35 and 36 they are engaged by the teeth 40, 40 of centering wheel 42. The function of centering wheel 42 is to align the cigarettes properly within the individual wrappers 44 for each cigarette. It will be observed that when the cigarettes leave separator 10, they are located within and at one end of the wrappers. Before the ends of the wrappers can be folded over the cigarette, it is therefore necessary that the cigarettes be centered within the wrapper so that substantially equal portions of wrapper extend beyond each end of each cigarette.

As the cigarettes proceed along screws 25 and 26, the ends of the wrappers 44 abut side plates 45 and 46. Plate 46 extends to and may be an extension of the vertical side of bracket 36 whereas plate 45 tapers somewhat in a forward

direction and terminates at a point just behind centering wheel 42. At the opposite end, both plates 45 and 46 extend longitudinally beyond the termini of screws 25 and 26 in bracket 28. As the cigarettes reach the termini of screws 25 and 26, they are fed underneath the periphery of a wheel or drum 47 which is mounted on shaft 48 and which is provided with a suitable friction surface 49 such as fine sandpaper or the like.

A pair of guards 50 and 51 are located in spaced relation over the top of screws 25 and 26 and extend longitudinally thereof from a point adjacent the zone at which the cigarettes are deposited onto the screws to the drum. At one end the guards 50 and 51 are pivotally supported at flared openings 38 and 39. At the other end they are permitted to rest lightly on the cigarettes and are bent upwardly backwards as shown in Fig. 4, at which point they are retained in transverse alignment by means of grooves 52 and 53 on the periphery of drum 47.

As the cigarettes are engaged by the periphery 49 of drum 47, they are rolled across a concave corrugated bed or depression 54, as shown in Fig. 4. The spacing of the upper surface of the bed 54 and the periphery 49 of drum 47 is sufficient to provide slight pressure between the cigarettes wrapper and the friction surface 49 of the drum. Bed 54 in the preferred form is arcuate in shape and substantially concentric with drum 47. The rotation of drum 47 causes the cigarettes to roll on their individual axes past the wrapping standards 55, 55 to overlap and fold the ends of wrapper 44 of each cigarette. A central groove 52a on the periphery of drum 47 provides clearance for the tear tab 44a of wrapper 44 so that the tabs will not be pressed onto the surface of the wrappers. The functioning of these wrapping standards 55, 55 is shown and described in my co-pending application, Serial Number 791,002, filed December 11, 1947.

I have found that the provision of a drum of relatively small diameter and the concave bed 54 greatly enhances the end folding operation. However, it is essential to the smooth functioning of the end folding mechanism that the cigarettes be properly fed to the drum. Proper feeding of the cigarettes at this point entails the exact timing for each cigarette so that jamming is eliminated and also so that maximum capacity can be attained. The speed at which screws 25 and 26 rotate can of course, be accurately controlled as well as the speed at which drum 47 rotates. Since the feeding of the cigarettes on the screws is of course fixed, the speed and timing of the feed to the drum and its associated folding structure can be precisely controlled. It is not dependent upon the friction or the amount of rolling that might be present between the cigarettes and a belt so that a positive feed to the folding mechanism is provided at all times.

After the folding operation described above the cigarettes are fed between brackets 56 and 57 also mounted on platform 37. Continued feeding of the cigarettes by drum 47 into brackets 56, 57 causes the cigarettes to push each other between the brackets until their ends are engaged by a pair of metallic belts 58 and 59 which are in turn mounted on pulleys 60, 61 and 62, 63. At this point the belts pass in front of the face plates 64a and 65a of electric heaters 64 and 65 by means of which the folded ends of the individual wrappers are heat sealed. The mate-

rial for belts 58 and 59 is preferably of some thin metal having good heat conductivity. Tension in belts 58 and 59 is provided by means of idler pulleys 61a and 63a which may be adjustable if desired. Heaters 64 and 65 are positioned over elongated slots 66 and 67 in platform 37 and are provided with suitable electrical connections 68, 68. After passing from control of belts 58 and 59, the fully wrapped and sealed individual cigarettes 12, 12' are deposited onto an endless belt 69 which is mounted over pulley 70 journaled on platform 37. Belt 69 is provided with a guard 71 to prevent the cigarettes from falling from the belt.

As shown clearly in Fig. 2 the axial spacing between threads 33 and 34 on screws 25 and 26 is relatively greater underneath separator 10 than opposite centering wheel 42, for example. This feature is important in assuring that the cigarettes always fall between successive threads on the screws. As the cigarettes proceed along the screws the thickness of the threads gradually increases until there is just sufficient clearance between the threads to loosely accommodate the individual cigarette. In this position the maximum distance between threads is substantially equal to, or slightly greater than the diameter of the cigarette and wrapper.

As the cigarettes reach the termini of screws 25 and 26, their continued course is controlled by drum 47 as explained above. After contact with the periphery of drum 47 ceases, the cigarettes push each other successively through brackets 56 and 57 until the ends of the cigarettes contact belts 58 and 59. As will be noted in Fig. 1, the forward ends of face plates 64a and 65a are flared slightly outwardly so that brackets 56 and 57 can guide the cigarettes between the belts, which at this point likewise flare outwardly to provide gradual engagement of the cigarettes without danger of crushing them.

It will thus be understood that I have provided a cigarette handling apparatus which positively and accurately controls the feeding of the cigarettes or other articles to the folding and sealing station. This accurate control in turn enables improvements to be made with respect to the folding and sealing structure and at the same time provides increased speed and a minimum of danger to the cigarettes.

Having thus described my invention, I claim:

1. In article handling machinery, the sub-combination which comprises a feed trough in which articles to be packaged are carried, a drum journaled above said trough, an arcuate bed in said trough, said bed being substantially concentric with said drum, means spaced along the sides of said arcuate bed for folding and wrapping the ends of articles fed between the drum and the groove, and means for feeding articles to be wrapped against the periphery of the drum.

2. Apparatus in accordance with claim 1 in which the periphery of the drum is provided with a friction face.

3. Apparatus in accordance with claim 1 in which the arcuate bed has a plurality of corrugations adapted to rotate the articles being wrapped.

4. Apparatus in accordance with claim 1 in which the drum is provided with at least one peripheral groove, and a guard adapted to be transversely retained by said peripheral groove.

5. Apparatus in accordance with claim 1 in which the drum is provided with a central periph-

eral groove, and a pair of guard retaining grooves.

6. In cigarette wrapping machinery having a pair of counter-rotating feed screws, means for depositing cigarettes on said feed screws, gear means for timing the rotation of said feed screws with respect to each other, the improvement that consists of a centering wheel journaled on a vertical axis and turnable in timed relation with the feed screws, means including a plurality of spaced teeth around the periphery of said wheel for consecutively contacting individual cigarettes straddling the top of both feed screws, and an abutment transversely opposite the centering wheel and in predetermined spaced relation thereto for aligning the cigarettes on the screws in cooperation with the centering wheel.

7. In cigarette wrapping machinery having a pair of counter-rotating feed screws, means for depositing cigarettes on said feed screws, gear means for timing the rotation of said feed screws with respect to each other, the improvement that consists of a centering wheel journaled on a vertical axis and turnable in timed relation with the feed screws, means including a plurality of spaced teeth around the periphery of said wheel for consecutively contacting individual cigarettes straddling the top of both feed screws, an abutment transversely opposite the centering wheel and in predetermined spaced relation thereto for aligning the cigarettes on the screws in cooperation with the centering wheel, an end wrapping station contiguous with the termini of the feed screws, a transverse arcuate trough comprising the bottom of said end wrapping station, a drum concentrically mounted with respect to said trough, said drum being journaled on a horizontal axis, a friction face on said drum, and guide means for directing cigarettes discharged from the feed screws into the clearance space between the drum and the depression.

8. In cigarette wrapping machinery having a pair of counter-rotating feed screws, means for depositing cigarettes on said feed screws, gear means for timing the rotation of said feed screws with respect to each other, the improvement that consists of a centering wheel journaled on a vertical axis and turnable in timed relation with the feed screws, means including a plurality of spaced teeth around the periphery of said wheel for consecutively contacting individual cigarettes straddling the top of both feed screws, an abutment transversely opposite the centering wheel and in predetermined spaced relation thereto for aligning the cigarettes on the screws in co-

operation with the centering wheel, an end wrapping station contiguous with the termini of the feed screws, a transverse arcuate trough comprising the bottom of said end wrapping station, a drum concentrically mounted with respect to said trough, said drum being journaled on a horizontal axis, a friction face on said drum, at least one annular groove around the periphery of said drum, and a guard extending into said groove to guide the cigarettes against the periphery of the drum.

9. In cigarette wrapping machinery having a pair of counter-rotating feed screws, means for depositing cigarettes on said feed screws, gear means for timing the rotation of said feed screws with respect to each other, the improvement that consists of a centering wheel journaled on a vertical axis and turnable in timed relation with the feed screws, means including a plurality of spaced teeth around the periphery of said wheel for consecutively contacting individual cigarettes straddling the top of both feed screws, an abutment transversely opposite the centering wheel and in predetermined spaced relation thereto for aligning the cigarettes on the screws in cooperation with the centering wheel, an end wrapping station contiguous with the termini of the feed screws, a transverse trough comprising the bottom of said end wrapping station, a drum concentrically mounted with respect to said trough, said drum being journaled on a horizontal axis, at least one annular groove around the periphery of said drum, and a guard extending into said groove to guide the cigarettes against the periphery of the drum.
